UNITED STATES PATENT OFFICE.

SETH H. LEAVENWORTH, OF CINCINNATI, OHIO, ASSIGNOR TO THE HOMAN SILVER PLATE COMPANY, OF CINCINNATI, OHIO, A CORPORATION.

DESIGN FOR A MOUNTING FOR METAL DISHES.

SPECIFICATION forming part of Design No. 36,280, dated April 7, 1903.

Application filed March 2, 1903. Serial No. 145,842. Term of patent 7 years.

To all whom it may concern:

Be it known that I, SETH H. LEAVENWORTH, a citizen of the United States, residing at Cincinnati, in the county of Hamilton and State 5 of Ohio, have invented and produced a new, original, and ornamental Design for a Mounting for Metal Dishes, of which the following is a specification, reference being had to the accompanying drawing, forming a part thereof.

10 The figure of the drawing is a plan view of the mounting.

The above ornamental design is an article of manufacture, and is adapted to be applied as a mounting to metal dishes and similar 15 articles as a decorating-border of various sizes and shapes.

As shown in the drawing, the leading or material feature of my design consists of a branch on which are displayed leaves, twigs, and 20 flowers. The flowers are conventional apple-

blossoms and in full relief. The twigs and leaves are conventional and displayed at intermediate points between the flowers. The twigs, leaves, and flowers are combined so as to produce an artistic effect and still preserve 25 the general characteristics of a mounting for a metal dish.

Having described my invention, what I claim as new, and desire to secure by Letters Patent, is—

30 The ornamental design for a mounting for metal dishes and similar articles as herein shown and described.

In testimony whereof I have hereunto set my hand.

SETH H. LEAVENWORTH.
